(57) **CLAIM**

The ornamental design for a grab handle, as shown and described.

DESCRIPTION

FIG. 1 is a front perspective view of a grab handle, showing my new design;

FIG. 2 is a front elevation view thereof;

FIG. 3 is a right side elevation view thereof;

FIG. 4 is a left side elevation view thereof;

FIG. 5 is a rear elevation view thereof;

FIG. 6 is a top view thereof; and,

FIG. 7 is a bottom view thereof.

The portions of the grab handle shown in broken lines form no part of the claimed design.
